United States Patent Office

Des. 230,172
Patented Jan. 29, 1974

230,172

FIGURE TOY VEHICLE

Adolph E. Goldfarb, Tarzana, Delmar K. Everitt, Woodland Hills, Ronald F. Chesley, La Crescenta, and Richard D. Friedich, Canoga Park, Calif., assignors to Mattel, Inc., Hawthorne, Calif.

Filed Apr. 28, 1972, Ser. No. 248,793

Term of patent 14 years

Int. Cl. D21—01

U.S. Cl. D34—15 AJ

FIG. 1

FIG. 2

FIG. 3

FIG. 1 is a left-side elevational view of the figure toy vehicle showing our new design;

FIG. 2 is a top plan view thereof;

FIG. 3 is a front elevational view thereof;

FIG. 4 is a right-side elevational view thereof;

FIG. 5 is a bottom view thereof; and

FIG. 6 is a rear plan view thereof.

We claim:

The ornamental design for a figure toy vehicle, as shown.
